UNITED STATES PATENT OFFICE.

WILLIAM M. WADLEIGH, OF CHICAGO, ILLINOIS.

ATTACHABLE GRAIN-ELEVATING GUARD.

1,250,251.

Specification of Letters Patent. Patented Dec. 18, 1917.

Application filed December 15, 1913. Serial No. 806,726.

To all whom it may concern:

Be it known that I, WILLIAM M. WADLEIGH, a citizen of the United States, residing in Chicago, in the county of Cook and 5 State of Illinois, have invented a new and useful Improvement in Attachable Grain-Elevating Guards, of which the following is a specification.

This invention relates to improvements in 10 attachable grain elevating guards and more particularly to improvements on the type of the grain elevating guard on which a patent was granted to me No. 733,442 on July 14, 1903.

15 Objects of the invention are to provide an adjustable grain elevating guard of the general type shown in my said patent and so constructed that the cost of assembling is materially decreased and which is further- 20 more provided with means for positively preventing too great a movement of the adjustable arm, said means also serving to prevent loss of the locking bolt and to prevent dust or dirt or other foreign matter 25 collecting in the pivotal connection between the stationary supporting arm and the adjustable arm.

The invention furthermore consists in the 30 improvements in the parts and devices and in the novel combination of the parts and devices herein shown, described or claimed.

In said drawing Figure 1 is a side elevation of a grain elevating guard embodying my improvements, the same being shown attached to the finger bar of a harvester or 35 like machine, the finger bar being shown in section. Fig. 2 is a detail part side elevation, part vertical section showing more clearly my improvements. Fig. 3 is a top plan of the structure shown in Fig. 1 and 40 Fig. 4 is a detail, vertical section taken on the line 4—4 of Fig. 2.

In said drawing 10 denotes the finger bar of a harvester or like machine having finger 45 guards 11 secured thereto and provided with a sickle 12 and sickle bar 13, all arranged and operating in any well known manner. The attachable grain elevating guard is designated generally by the reference A and 50 the same comprises a lower stationary supporting arm 14 recessed at its rear end as at 15, thus providing lower and upper fingers 16 and 17 respectively, the upper finger 17 being slightly resilient to adapt the attachment to be secured to different sized 55 finger bars, the lower arm of the attachment

being secured in place by a bolt 18 and nut 19. The lower arm 14 extends forwardly and downwardly for the greater part of its length and is provided with a short upwardly inclined bottom face 20 at its forward end and is pointed, as shown at 21. The point 21 is connected to the upper face of the main portion of the supporting arm 14 by a narrow web 22 cast integrally therewith. The adjustable arm 23 is pivoted to the web 22 by pivot pin or rivet 24, the lower front end of the arm 23 being forked as at 25, 25 to straddle the web 22. The pivoted arm 23 is recessed as at 26 and slidably 70 mounted therein is a locking bolt 27 normally pressed outwardly by a spring 28, the locking bolt having a finger piece 29 thereon by which it is manipulated. The locking bolt engages in and cooperates with notches 130 75 formed on the rear edge of the web 22 to thereby hold the arm 23 in any of its several positions. The pointed end 21 of the supporting arm is provided with a relatively wide, upwardly and rearwardly extending 80 flange or lip 30 which extends over the upper surface 31 of the adjustable arm 23, as shown most clearly in Fig. 2. This flange or lip 30 is also extended in width so as to cover the joints 32 formed between the web 85 22 and the forked ends 25 of the arm 23. The lower ends of the forked arms 25 are rounded and the point 21 is also rounded as at 33 to correspond therewith and permit 90 free movement of the arm 23.

The flange 30 which extends over the upper surface of the adjustable arm 23 will positively prevent the latter from being swung up more than the amount shown in Fig. 2, or in other words the flange 30 95 serves as a limiting stop. By providing this flange, I am enabled to assemble the parts much quicker, and without the necessity of any filing or other adjustment, than is possible in the construction shown in my 100 said Patent No. 733,442. In the patented construction, the adjustable pivoted arm and the supporting arm were provided with small narrow shoulders which necessitated the accurate location of the pivot receiving 105 holes in the two arms and also the filing of the two engaging shoulders. In the present improved construction, the pivot receiving holes of the two members do not require such nicety of location as in the patented 110 structure and filing of the parts to insure the proper adjustment is entirely done away

with and I have found that the cost of assembling the improved structure described herein is approximately fifty per cent. less than the cost of assembling the device shown in my said patent. Another advantage secured by the present construction lies in the fact that no matter how carelessly the operator may lift up the adjustable arm 23, he cannot swing it beyond the position shown in Fig. 2 so that there is no danger of the locking bolt and spring falling out. In the structure shown in my said patent, the operator in lifting the pivoted, adjustable arm, oftentimes swung it past its highest position with the result that the locking bolt and spring would fall out. This was due to the fact that the extremely small and finely adjusted engaging shoulders on the pivoted arm and supporting arm soon wore off and permitted the pivoted arm to be swung far beyond its intended uppermost position. Another advantage inherent in my improved construction resides in the fact that the flange 30 is made of such width as to completely cover the two joints 32 between the pivoted parts and thereby prevents the lodgment of any dirt, dust or other foreign matter therein which would interfere with the easy adjustment of the pivoted arm.

Although I have herein shown and described what I now consider the preferred embodiment of my improvement, yet it will

be understood that various changes and modifications may be made without departing from the spirit of the invention, and all such changes and modifications are contemplated as come within the scope of the claim appended hereto. ³⁵

I claim:—

A detachable grain elevator guard for 40 harvesters and the like, comprising a supporting arm having a pointed front end and recessed at each side back of said end to provide a central web, and an elevating arm bifurcated at its lower end and thereby embracing said web with its side portions resting in said recesses and pivoted to said web, said arms having interlocking parts one of which is movable, whereby the elevating arm is held in adjusted elevated position, 45 said supporting arm having a rearwardly extending lip engaging over the elevating arm above said pivot and acting as a stop to limit the upward movement of the elevating arm and maintain said interlocking parts 50 from passing beyond their operative relation. ⁵⁵

Signed at Chicago, Illinois, this 11th day of December, 1913, in the presence of two subscribing witnesses.

WILLIAM M. WADLEIGH.
